UNITED STATES PATENT OFFICE.

LINCOLN HAUSMANN, OF NEW YORK, N. Y.

ROTARY ENGINE.

SPECIFICATION forming part of Letters Patent No. 430,342, dated June 17, 1890.

Application filed December 30, 1887. Serial No. 259,382. (No model.)

To all whom it may concern:

Be it known that I, LINCOLN HAUSMANN, of the city, county, and State of New York, have invented a new and Improved Rotary Engine, of which the following is a full, clear, and exact description.

Reference is to be had to the accompanying drawings, forming a part of this specification, in which similar letters of reference indicate corresponding parts in both the figures.

Figure 1 is a broken side elevation of my new and improved rotary engine; and Fig. 2 is a transverse sectional elevation of the same, taken on the line *x x* of Fig. 1.

15 The invention will first be described in connection with the drawings, and then pointed out in the claims.

A represents an annular steam-chest made, by preference, of a tube formed with a slot 20 B at its periphery. In this slot is fitted the inner edge of the annular plate or disk C. Secured to the inner edge of this disk is a piston-head D, which fits the circular cavity of the steam-chest A, as shown clearly in Fig. 25 2, so that when steam is admitted to the steam-chest through induction-pipe E the said piston and annular disk C will be forced around the steam-chest A. That portion of the annular disk C which enters the slot B 30 and the surfaces of said slot are correspondingly corrugated to prevent the escape of steam. The exhaust of steam from the steam-chest is through the pipe E or E', according to the direction of motion required. Between the said two pipes E E' is fitted in the chest A the sliding valve or cut-off plate F, fitted in a transverse slot or opening F'. This valve or plate is operated out and in by

two levers G G', fulcrumed, respectively, in the arms H H'. The lower end of the lever 40 G is connected to the short arm of the lever G' by the connecting-rod J, and the long arm of the said lever G' is connected to the plate F by the connecting-rod J'. The upper end of the lever G is bent over to stand near the 45 annular disk C, and on said disk, nearly in line with the piston-head D, is formed the cam K, which is adapted to strike the upper end of the lever G just before the piston-head D reaches the valve F, and force said upper end of the lever outward and cause lever G' to draw the valve F outward and allow the piston-head to pass and permit the exhaust. After the piston-head D has passed the valve F the said valve is returned by the action of 50 55 the spring L. (Shown in Fig. 2.)

Having thus fully described my invention, I claim as new and desire to secure by Letters Patent—

1. The annular steam-chest A, slotted at 60 B, the annular disk C, fitted in said slot, the piston-head D, attached to the annular disk, and the valve F, in combination with the levers G G', connecting-rods J J', and the cam K, formed on the disk C, substantially as and 65 for the purposes set forth.

2. The annular steam-chest A, slotted at B around its periphery, and slotted at F', in combination with the annular disk C, piston-head D, and cut-off valve F, substantially as 70 described.

LINCOLN HAUSMANN.
